APPARATUS FOR TESTING THE EMBRITTLEMENT CRACKING CHARACTERISTICS OF SOLUTIONS

Wilburn C. Schroeder, Hyattsville, and Abraham A. Berk, Berwyn, Md., assignors to the Government of the United States of America, as represented by the Secretary of the Interior and his successors in office

Application October 12, 1938, Serial No. 234,722
5 Claims. (Cl. 73—51)

(Granted under the act of March 3, 1883, as amended April 30, 1928; 370 O. G. 757)

The invention described herein may be manufactured and used by or for the Government of the United States for governmental purposes only without the payment of any royalty thereon.

This invention relates to an apparatus for testing the embrittling or intercrystalline cracking characteristics of water used in an operating boiler or of solutions used in other metal vessels.

Serious difficulties from embrittlement in boilers, digesters, etc., have been encountered and recognized for a number of years. Investigation has clearly shown that dilute alkaline solutions, such as used in boiler operation, will not cause embrittleness cracking. For example, water in a boiler will seldom contain more than a few thousand parts per million of sodium hydroxide, and at such a degree of dilution, the water cannot cause embrittleness cracking of tube ends, riveted seams, etc. In the laboratory, it has been found that from 50,000 to 500,000 parts per million of sodium hydroxide are usually necessary to cause cracking.

Our investigations have shown that if a dilute boiler water, or solution, is concentrated by evaporation it can produce embrittleness cracks and failures in steel which is maintained under stress in contact with such concentrated solution. Concentration easily can be accomplished by withdrawing a sample of water from the boiler and evaporating it until it contains from 200,000 to 500,000 parts per million of sodium hydroxide. Such concentrated solution, heated to the atmospheric boiling temperature, or to a higher temperature under pressure, can be placed in contact with a stressed steel specimen, and if intercrystalline cracking results, the water is a dangerous one and may cause embrittleness cracking in the boiler metal.

Concentration of the dilute water solution also can be produced directly in contact with a stressed specimen instead of being concentrated and later brought into contact with the specimen. A number of tests have been made with apparatus of this character wherein the dilute boiler water has been placed in a receptacle having a small space one wall of which is formed by the stressed specimen to be tested, and the device is placed in a furnace or other heating equipment to be brought up to the temperature

at which it is desired to conduct the test. Steam thus generated is slowly bled off to permit concentration of the boiler water in the device, which is commonly known as a "bomb." The small space referred to is usually annular and by making such space quite narrow, it is possible to concentrate the boiler water many hundredfold. The stress can be applied to the specimen in any desired manner, either internally or externally, and it may be provided before the test is started and/or at any time during the test.

If the initial sodium hydroxide concentration of the boiler water is known, the final concentration attained in the bomb can be determined by condensing and measuring the steam which is driven off. The solution can be maintained at any desired concentration by closing a bleed valve.

Concentration of the dilute boiler water also can be secured without actually bleeding off steam from the device. For example, if a closed container is provided with a depending hollow member in which the specimen is arranged, and wherein small clearance is provided between the specimen and the depending hollow member, heat may be applied to such member. Under such conditions, steam will be generated in the small space adjacent the specimen and the steam will pass upwardly into the receptacle, thus leaving a concentrated solution in contact with the specimen. As in the previous case, the specimen may be maintained under stress in any desired manner to determine whether embrittleness cracking of the metal will occur.

In steam boiler operation, or in other metal vessels, embrittleness cracking is found in rivets, butt straps, drum sheets, tube ends, etc., that are at the same temperature as the boiler water and therefore could not cause solution concentration by evaporation against the boiler pressure or evaporation in accordance with the test methods referred to above. This obviously is true for the reason that the rivet heads and other elements referred to do not have sources of heat supply which could cause the evaporation.

In the testing methods referred to above, concentration of the boiler water or other solution requires that a specimen of the water be removed from the boiler or other vessel or isolated in a

separate vessel attached to the boiler with suitable level control devices before the test is started. This may create unknown and unaccountable changes that greatly influence the embrittlement cracking. Moreover, the conditions that produce cracking in either of the test methods referred to are not necessarily the same as those that cause embrittlement of the metals comprising the parts or elements of the boiler or vessel.

An important object of the present invention is to provide a novel apparatus for testing the embrittlement cracking characteristics of boiler water or other solutions wherein actual operating conditions are reproduced.

A further object is to provide a novel apparatus of the character referred to wherein the solution is led directly from the boiler or other vessel over a test specimen under conditions reproducing actual conditions within the boiler or other vessel whereby any changes occurring in the boiler will be reproduced during the practice of the method and thus provide accurate information as to the characteristics of the solution.

A further object is to provide a novel apparatus wherein water or other solution from a boiler or other vessel is led directly over a specimen to be tested in a reduced restricted flow whereby concentration of the solution will occur against the specimen to reproduce conditions which are occurring within the seams or other restricted spaces in a boiler or on other metal surfaces in other vessels at points where embrittlement cracking usually occurs.

A further object is to provide such an apparatus wherein evaporation of the solution takes place from the side of the specimen opposite that at which the solution is fed thereto to effect a concentration of the solution in contact with the specimen, the latter being maintained under stress during the practice of the method as is true of the parts of a boiler or other vessel where embrittlement cracking usually occurs.

A further object is to provide a novel apparatus wherein the normal operating conditions in a boiler or the like are accurately reproduced so that the results obtained by the apparatus are accurate indications of the embrittlement characteristics of the solution in the boiler or the like.

A further object is to provide an apparatus having a restricted passage for the flow of boiler water or the like directly from the boiler or other vessel and wherein a specimen under stress forms one wall of the restricted passage, and wherein evaporation of the solution and the concentration thereof will occur in contact with the specimen to reproduce conditions within the boiler or other vessel.

A further object is to provide a novel apparatus of the character just referred to wherein evaporation is caused to take place at the end of the restricted passage opposite the end to which the solution is introduced to facilitate the concentration of the solution in contact with the specimen.

Other objects and advantages of the invention will become apparent during the course of the following description.

We have discovered that the conditions under which embrittlement cracking occurs in boilers or other vessels may be closely simulated or exactly reproduced so as to render a test device of this general character far more accurate and dependable in its results. In accordance with

the present invention, therefore, water is led directly from the boiler or other vessel into the testing device and a flow of the water is provided at a slow rate through a restricted space one wall of which is formed by the test specimen, approximate boiler temperature being maintained at the test point to assist in simulating or reproducing actual conditions at points within a boiler or the like where embrittlement cracking takes place. During passage through the restricted space pressure is released and steam escapes toward the atmosphere through an outlet pipe preferably controlled by a bleed valve whereby the rate of flow of the escaping fluid can be controlled, such fluid, of course, being in the form of steam developing incident to the releasing of the pressure.

The rate at which pressure is released by permitting the escape of steam, together with the restriction of the space through which the solution flows past the specimen will determine the rate of flow of the solution past the specimen, and accordingly any desired rate of concentration adjacent to the specimen can be provided. This restricted space, as indicated above, constitutes a simulation of conditions that exist in a riveted seam or rolled in tube end or other place in a boiler in which embrittlement cracking is commonly encountered. As the boiler water passes through the seam or rolled in tube end it progresses toward a region of lower or atmospheric pressure and therefore due to its high temperature this drop in pressure causes the escape of steam toward the atmosphere and the consequent concentration of the solution remaining in the restricted passage. The conditions created in the equipment described in this invention duplicate these conditions existing in the riveted seams or rolled in tubes or other restricted spaces in the boiler.

The specimen being tested obviously is maintained under stress during the test, and the stress may be internal and/or external, and it may be applied before or during the test and maintained throughout the test. It will be apparent therefore that the test exactly duplicates the conditions that cause embrittlement of the rivets, butt straps, etc., and can be operated continuously on the boiler or vessel so that any change which creates a dangerous condition in the water will be immediately discovered. With the proper instructions, the test can be conducted without special skill or training, and complete control is provided over the operation of the equipment. In waters or solutions that are treated to render them incapable of producing embrittlement cracks, the test obviously can be used to estimate the effectiveness of the treatment employed.

Somewhat more specifically, our experiments have indicated that the solution from a steam boiler or other vessel may be very easily concentrated to produce embrittlement cracking by allowing it to leak or diffuse through a small opening more slowly than it is permitted to evaporate on the other side of the leak or opening by providing the steam escape control means referred to.

In the drawing we have shown several types of apparatus particularly adapted for practicing the method. In this showing,

Figure 1 is a sectional view showing one type of apparatus wherein the specimen is spring loaded to be maintained under stress,

Figure 2 is a similar view of a modified form

of the invention wherein the spring loading is transmitted to the specimen longitudinally thereof and is supplemented by lateral stressing means.

Figure 3 is a similar view showing another modification wherein a substantially cylindrical specimen is maintained under stress by being driven into position on a plug or the like, and,

Figure 4 is a similar view of a further modification wherein a conical stretcher is employed for the specimen and wherein the flow space around the specimen may be adjusted.

Referring to Figure 1 the numeral 10 designates a receptacle shown in the present instance as in the form of a cast body having a passage 11 therethrough into one end of which is threaded a pipe 12 connected to the boiler or other receptacle to feed directly therefrom the water or other solution to be tested. A pipe 13 is threaded in the other end of the body 10 and is provided with a take-off pipe 14 preferably provided with a control valve 15, and the pipe 14 preferably leads to a suitable condenser.

Between the adjacent ends of the pipes 12 and 13 a test specimen indicated as a whole by the numeral 16 is arranged within the passage 11, the space 17 surrounding the specimen constituting a solution concentrating chamber, as will become apparent. The specimen is hollow, as shown and is provided at its lower end with an annular flange 18 forming a restricted annular passage 19 for the flow of water. The upper end of the flange 18 engages lugs 20, extending into the bore 11, to limit upward movement of the specimen. The specimen is provided intermediate its ends with a relatively thin cylindrical wall 21 at some point along which the embrittlement cracking is adapted to occur.

The specimen is provided at its upper end with a head 22 through which extends a stem 23 having a head 24 at its lower end engaging the lower face of the head 22 to exert an upward force for maintaining the specimen under stress, as will become apparent. The stem 23 extends through a plug 25 mounted in the upper end of the pipe 13. A spring seat 26 surrounds the stem 23 at a point spaced from the plug 25, and a relatively heavy compression loading spring 27 surrounds the stem 23 between the plug 25 and spring seat 26. A thrust bearing 28 is preferably arranged above and in engagement with the spring seat 26, and a nut 29 is threaded on the upper end of the stem 23. The upper extremity of the stem 23 may be formed polygonal as at 30 for engagement with a wrench to prevent turning movement of the stem 23 while the nut 29 is being turned.

A particularly advantageous form of the invention is shown in Figure 2 wherein the specimen is subjected to both axial and transverse stresses. A body 31 is provided with a chamber 32, and a cap 33 in the lower end of the body is tapped as at 34 for connection with a pipe leading to the boiler to supply boiler water to the chamber 32. The body 31 also may be provided with an opening 35, connected to the boiler, whereby a circulation may be maintained through the chamber 32. The upper end of the body 31 is provided with a concentrating space 36 adapted to communicate with the chamber 32 through a seat 37. The space 36 is provided with a radial port 38 from which a pipe 39 may lead to a suitable condenser.

The specimen to be tested is indicated as a whole by the numeral 40 and comprises a stem 75

41 threaded at its upper end as at 42 for a purpose to be described. The stem 41 extends downwardly through the upper end of the body 31 and is provided with a reduced test portion 43 within the space 36. Below the test portion the specimen is provided with a conical portion 44 for at least partially closing the seat 37. Below the conical portion 44 the specimen is provided with a depending cylindrical portion 45. A suitable packing gland 46 may be provided to prevent leakage past the stem 41.

The body 31 is provided near one side with a threaded opening for the reception of a plug 47 in which is arranged a stem 48, this stem being provided with a threaded portion 49 engaging a similarly threaded opening in the plug 47. The inner end 50 of the stem 48 is engageable against the lower end 45 of the specimen and it will be apparent that upon the application of a wrench to the polygonal outer end 51 of the stem 48, the latter may be turned in the plug 47 to cause the inner end 50 of the stem to exert a lateral force against the lower end 45 of the specimen. The stem 48 may extend through a suitable packing gland 52 carried by the plug 47.

A supporting sleeve 53 has its lower end threaded on an axial extension 54 carried by the body 31, and the upper end of the sleeve 53 carries a spring seat 55. A stem 56 has its lower end extending into the sleeve 53 and enlarged as at 57 to receive the threaded upper end 42 of the specimen. A spring seat 58 is slideable on the stem 56 and a heavy tension spring 59 surrounds the stem 56 and engages the seats 55 and 58. A thrust bearing 60 surrounds the stem 56 and engages the upper face of the spring seat 58 and a nut 61 engages the thrust bearing to turn it downwardly or upwardly to adjust the tension of the spring 59. The upper end of the stem 56 may be made polygonal as at 62 to be engaged by a wrench and thus hold the stem 56 against turning while the nut 61 is being adjusted. It will become apparent that the spring 59 exerts an upward force on the stem 56 to maintain the specimen under a static tensile load.

In the form of the invention shown in Figure 3 a body 63 is provided with a passage 64 into the lower end of which is tapped a pipe 65 to supply water from the boiler or other nozzle. A cap member 66 is threaded in the upper end of the bore and is provided with a steam escape pipe 67. This pipe also may be provided with a control valve 68 and may lead to a suitable condenser. A specimen support 69, in the form of a substantially cylindrical plug, is supported in the passage 64 by lugs 70 and may be held in the position shown in Figure 3 by a suitable spring 71. The plug 69 is surrounded by a relatively thin substantially cylindrical specimen 72 which is driven into position on the plug 69 to be thus maintained under substantial tension. The passage 64 forms a chamber 73 within the body 63 and the lower end of this chamber is defined by the relatively narrow annular space 74 surrounding the specimen 72 and forming a solution concentrating space, as will become apparent.

A somewhat different form of the invention is shown in Figure 4 wherein a body 75 is provided with a chamber 76 one end of which is tapered as at 77. The corresponding end of the body is tapped as at 78 for the reception of a pipe leading to the boiler whereby water may be supplied to the chamber. The other end of the body is provided with a plug 79 in which is

threaded a stem 80 having a conical head 81 at one end. A specimen 82 is formed of relatively thin steel and coincides in shape and size to the conical head 81 to surround the latter. The smaller end of the head 81 is threaded as at 83 to receive a nut 84, whereby the specimen 82 may be forced toward the larger end of the head 81 to be placed under static circumferential tension. Between the head 81 and the plug 78, the body 75 is ported as at 85 for connection with a pipe 86 which may lead to a conventional condenser.

The operation of the form of the invention shown in Figure 1 is as follows:

With the parts assembled as shown, boiler water or other solution may be admitted through the pipe 12 into the chamber 17. The solution has a restricted flow through the passage 19, and thence past the test portion 21 of the specimen, the chamber 17 around such portion of the specimen forming a restricted concentrating space for the solution, simulating restricted spaces of slow flow within a boiler at which points embrittlement cracking usually takes place.

Pressure is released by opening the valve 15 to the proper extent, in which case the boiler water is converted into steam at a rate depending upon the degree of opening of the valve 15. This action causes concentration of the solution in the space around the test portion of the specimen. It will be apparent that the space around the annular shoulder 18 is somewhat exaggerated and in actual practice only a slight leakage is provided so that there will be an extremely slow flow of solution into the chamber 17.

The spring 27 is relatively heavy and its tension is adjusted by turning the nut 29, preferably while engaging the polygonal head 30 with a wrench to prevent the turning of the stem 23. It will be apparent that the spring 27 exerts an upward force on the upper end of the specimen while the lower end of the latter is engaged by the lugs 20 to prevent its upward movement. Accordingly the spring 27 acts to maintain any desired static tensile load on the specimen.

As is true in all forms of the invention shown, the device in Figure 1 meets the essential requirement that self-evaporation in the boiler water or other solution takes place while in contact with the stressed specimen. The device operates by allowing leakage or diffusion of the solution through a small opening provided around the flange 18 more slowly than evaporation takes place on the other side of the leak, and accordingly self-evaporation takes place in contact with the specimen, as stated. It will be apparent that the connection of the device with the boiler or other vessel renders the device sensitive to any changes which take place in the source of the solution, and the heat of the source is maintained as well as the pressure in the source except for the slight drop in pressure occurring incident to the opening of the valve 15. It will be apparent that after a period of time concentration takes place in contact with the specimen in the same manner that it takes place adjacent to the metal or parts in the boiler which are usually subject to embrittlement cracking, and if such cracking of the specimen takes place, the solution may be dangerous for use in a boiler.

The leakage which takes place around the flange 18 must be slow enough so that the solution can evaporate and deposit its dissolved solid 75

in the annular space around the test portion 21 of the specimen. Either steam or a solution more dilute than that entering through the pipe 12 must be taken off through the pipe 14. In a 5 test equipment, the device has been connected to a pressure vessel containing 2,000 parts per million of sodium hydroxide at 200 lb. gage pressure, and it was possible to tap off almost pure steam through the pipe 14 and leave 0.3 gram of 10 sodium hydroxide in the annular space surrounding the test portion of the specimen. The actual sodium hydroxide concentration reached in such space was greater than 500,000 parts per million.

The form of the invention illustrated in Figure 15 2 is quite similar to that shown in Figure 1 except that the specimen is of a different type and is subjected both to axial and transverse stresses. After the spring 59 has been provided with a 20 predetermined loading, which obviously will hold the conical element 44 on the seat 37 to act as a valve thereagainst, the stem 48 may be turned inwardly to exert a lateral force against the lower end 45 of the specimen. This operation provides a lateral stress against the specimen and 25 also sufficiently unseats the conical member 44 at the side adjacent the stem 48 to permit a leakage between the chamber 32 and the concentrating space 36.

The pipe 39, of course, will be valve controlled 30 to determine the rate of exhaustion of steam from the space 36 and consequently the rate of evaporation therein. Concentration of the solution in the space 36, therefore, renders the device in Figure 2 similar in this respect to the operation of the device shown in Figure 1. The mechanism shown in Figure 2 is advantageous in that it provides the two different stresses referred to and for the additional reason that it provides communication through two openings (34 and 35) 35 with the boiler or other vessel to maintain a circulation through the chamber 32 so that the solution therein will always correspond to the solution in the boiler or other vessel regardless of any changes which take place therein. Accordingly the device closely simulates or reproduces conditions in the boiler or vessel. As in the form previously described, embrittlement cracking of the specimen indicates that the use of the solution is dangerous. In both of the forms of 45 the invention described, breakage of the specimen is immediately visually indicated by the releasing of the stem 23 or 56 by the springs acting upwardly thereagainst.

The form of the invention shown in Figure 3 55 is simpler than the form described but provides no visible indication of breakage of the specimen. Very slow leakage takes place around the lower end of the plug 69, the space through which this leakage takes place being exaggerated in Figure 60 3. Leakage of steam through the pipe 67 is controlled to determine the rate of concentration of the solution in contact with the specimen. The plug 69 and specimen are substantially cylindrical and the specimen is driven into position to be placed under a static circumferential stress.

The form of the invention shown in Figure 4 65 provides the same result as in Figure 3, the specimen being placed under circumferential stress by tightening the nut 84 to force the specimen toward the larger end of the head 81 and thus tend to stretch it. The forms of the device shown in Figures 3 and 4, as in the previous cases, are adapted to be connected to the boiler or other vessel, and the device in Figure 4 is initially

opened to the boiler through the opening 18 with the stem 80 turned inwardly to seat the specimen against the conical portion 11 of the chamber 16. The stem 80 then may be backed out to a small extent to provide the desired leakage past the specimen. This leakage, as is also true in Figure 3, provides a flow of solution past the specimen at a rate slower than the rate of evaporation of the solution in contact with the specimen whereby self-concentration of the solution takes place in contact with the specimen.

From the foregoing it will be apparent that the present invention provides a test bomb for determining the embrittlement cracking characteristics of boiler water and other solutions, the testing taking place under conditions closely approximating conditions within the seams, rolled in tube ends or other restricted spaces in the boiler or other vessel. The direct feeding of boiler water to either form of the device insures the testing under temperature conditions approximating those of the boiler, and the slow leakage provided through the valves 15 etc. maintain pressure in the device not greatly below the pressure in the boiler or the like, thus likewise closely reproducing pressure conditions in the boiler during the testing operation. The form of the device shown in Figure 2 is particularly advantageous for the reason that it provides stresses in two directions on the test specimen, and for the additional reason that it provides for the circulation of the solution through the two openings 34 and 35, thus maintaining in the chamber 32 a solution which is always the same as the solution in the boiler or other vessel.

While each form of the invention has been shown as being provided with means for maintaining a static tensile load on the test specimen, it will be apparent that the specimen may be provided with internal stresses by cold working or other methods of manufacture. Applied stresses may be created by any applied load, static and/or fatigue, etc., or there may be a combination of internal and applied stresses. The essential requirement of the invention, as indicated above, is that the equipment must provide self-evaporation of the solution in contact with the stressed specimen.

The present invention, therefore, contemplates the reproduction in contact with a stressed specimen of conditions which exist in the boiler or vessel or in restricted spaces therein in which the solution is being employed. More specifically, the invention contemplates the slow leaking or diffusing of the solution from the vessel through a constriction, and removing steam or vapor at the low pressure side of the constriction containing a lower concentration of dissolved solid than the entering liquid. In other words, the invention contemplates the maintenance of a slow flow of solution over a test specimen, such flow being at a rate slower than the rate of evaporation on the side of the specimen opposite that through which the solution is introduced. The steam or vapor may be removed under atmospheric pressure or above or below atmospheric pressure.

The various forms of the device illustrated are preferably directly attached to a boiler or other vessel and the forms of the invention shown in Figures 1 and 2 will automatically warn the operator when the water becomes dangerous and tends to cause embrittlement cracking. The device is particularly advantageous for use in determining the amount of a chemical to be added

to boiler water or other solution to prevent embrittlement cracking. The device also is particularly useful in determining the embrittlement cracking characteristics of any particular steel or metal alloy. Obviously the device will allow the determination of the total safe load a given metal can carry in contact with a given solution.

It is to be understood that the forms of the apparatus illustrated and described are to be taken as preferred examples of the same, and that various changes in the shape, size and arrangement of parts of the apparatus may be made without departing from the spirit of the invention or the scope of the subjoined claims.

We claim:

1. Apparatus for testing the embrittlement cracking characteristics of a solution, comprising a body having a passage therein, means for supporting and maintaining under stress a test specimen arranged within and intermediate the ends of said passage, means for supplying solution to be tested to one end of said passage, and means for evaporating solution from the other end of said passage to concentrate the solution in contact with the specimen.

2. Apparatus for testing the embrittlement cracking characteristics of a solution, comprising a body having a passage therein, means for supporting and maintaining under stress a test specimen arranged within and intermediate the ends of said passage, means for supplying solution to be tested to one end of said passage, means for restricting the flow of solution from said last named means through said passage, and means for evaporating solution from the other end of said passage at a rate greater than the rate of flow of the solution to said passage to concentrate the solution in contact with the specimen.

3. Apparatus for testing the embrittlement cracking characteristics of a solution, comprising means providing one passage for substantially free and continuous circulation of solution from a body of solution to be tested into one end and through said passage and from the other end thereof back to said body of solution to be tested, means providing another passage for receiving solution at one end thereof from said one passage, means for supporting and maintaining under stress a test specimen arranged within and intermediate the ends of said another passage, and means for evaporating solution from the other end of said another passage to concentrate the solution in contact with the specimen.

4. Apparatus for testing the embrittlement cracking characteristics of a solution, comprising means provided one passage for substantially free and continuous circulation of solution from a body solution to be tested into one end and through said passage and from the other end thereof back to said body of solution to be tested, means providing another passage for receiving solution at one end thereof from said one passage, means for supporting and maintaining under stress a test specimen arranged within and intermediate the ends of said another passage, means for restricting the flow of solution from said one passage through said another passage, and means for evaporating solution from the other end of said another passage at a greater rate than the rate of flow of solution to said another passage to concentrate the solution in contact with the specimen.

5. The combination with a steam boiler or other vessel, of means for testing the embrittlement cracking characteristics of the solution in

the vessel, comprising a body having a passage therein, means providing another passage for substantially free and continuous circulation of solution from said vessel to the passage in said body and from the latter passage to said vessel, 5 means for supporting a specimen in the passage

in said body and maintaining it under stress, and means for providing a restricted escape of vapor from the latter passage to concentrate the solution in contact with the specimen.
